UNITED STATES PATENT OFFICE.

JONATHAN PETERSON, OF BROOKLYN, NEW YORK.

POCKET BOX OR CONTAINER.

1,344,650.

Specification of Letters Patent. Patented June 29, 1920.

Application filed December 20, 1916. Serial No. 137,944.

To all whom it may concern:

Be it known that I, JONATHAN PETERSON, a citizen of the United States, residing at 746 St. Marks avenue, Brooklyn, in the 5 county of Kings and State of New York, have invented certain new and useful Improvements in Pocket Boxes or Containers, of which the following is a specification.

This invention relates to improvements in 10 boxes or other commodity containers, especially of the type which are conveniently carried in the pocket and adapted to be opened at will without affecting the closure, the arrangement being such as to prevent 15 sifting or leakage of the contents from the container.

The container of the present invention is designed more particularly as a receptacle and carrier for finely-divided or powdered 20 materials, such for instance as snuff. Material of this type, especially when in powdered form, readily escapes from its container, sifting therefrom through small crevices, such as may result by the application 25 of pressure to the container walls, a loose closure, etc.

As the snuff user generally carries the snuff with him, the container should be of such configuration as to be conveniently carried 30 in the pocket. The practice, generally, especially with dry snuff, is to employ long boxes of circular contour, the open top being normally closed by a suitable closure.

Containers of the circular type inherently 35 tend to prevent distortion of the walls at the open end due to the curvature of the container, thus enabling the use of a tight fitting closure, but such structure requires careful manipulation in applying the closure. 40

45 The present invention is designed to meet these and other conditions by changing the shape of the container so as to provide a partially flat instead of circular contour to the container on a cross section of the body. 50

This provides for comparatively large capacity combined with a shape fitted for and conveniently carried in the pocket without producing a bulky appearance to the container or the pocket.

55 Another feature is the transverse bracing of the walls of the body portion, especially

at the mouth or open end, thereby preventing inward collapsing of such walls in use.

An additional feature is the form of the closure which not only permits of a ready seating and unseating action, but which, in addition, has a configuration which will enable it to be used to readily remove contents from the interior of the container.

To these and other ends, the nature of 65 which will be readily understood as the invention is hereinafter disclosed, said invention consists in the improved construction and combination of parts, hereinafter fully described, illustrated in the accompanying drawings and more particularly pointed out in the accompanying claim.

In the drawings in which similar reference characters indicate similar parts in each of the views—

75 Figure 1 is a perspective view of a container according to my invention, the container being shown closed.

Figure 2 is a similar view with the closure removed and extending into the container to 80 act as a commodity-removing implement.

Fig. 3 is a side elevation.

Fig. 4 is a sectional view taken on line 4—4 of Fig. 3.

Fig. 5 is a sectional view taken on line 85 5—5 of Fig. 4.

In the drawing 10 designates the body portion of the container preferably formed of paper-board or other fibrous material, although other material may be employed 90 for the purpose.

The body portion is formed in suitable manner, the cross sectional contour however, having opposite sides 11 flattened and connected by curved portions 12, thus eliminating angular corners within the body portion.

The bottom 13 may be of suitable form and material. For instance, it may be formed integral with the body, but it is 100 preferably formed as a separate element and secured to the body in any desired manner, the connection being preferably such as to prevent sifting of the material through the connection.

105 The bottom may be formed of metal or of non-metallic material as desired.

The closure 14 is preferably metallic and formed from sheet material by suitable dies. As shown, the closure is formed with an annular depression produced by an outer flange or wall 14^a—which is adapted to fit the outer

periphery of the open end of the body—and a return wall 14^b, preferably of less axial length than wall 14^a, said walls combining to form the depression 14^c. Obviously, walls 14^a and 14^b may be termed rising and descending walls respectively. While the opposite side portions of wall 14^a are preferably parallel so as to fit the outer face of the body, this accurate formation is not required with respect to wall 14^b, the latter, as shown, being slightly inclined inwardly to increase the width of the depression toward the depression entrance, the bottom of the depression however preferably having a width equal to the thickness of the body portion wall at its open end.

By this arrangement, the open end of the body seats in the depression, wall 14^a surrounding such end, while wall 14^b extends inward. When seated, wall 14^b effectively prevents inward collapsing of the side walls of the open end of the body portion under pressure, thus preserving the practically close fit of wall 14^a and the body portion within the depression, thereby preventing sifting of the material from the box or container.

The descending wall 14^b places that portion of the body of the closure within the wall on a depressed plane with respect to the bottom of the depression. However, I prefer to raise a portion of the material of this closure body portion, as at 14^e, thus providing a rib formation throughout the major portion of the body of the closure, said rib preferably extending beyond a point midway of the length of the sides.

By this arrangement the closure portion internal of wall 14^b extends on two planes, 40 depressed portion 14^f being on the plane of the rib and preferably located at one end of the closure, portion 14^e being raised with respect to such plane.

Wall 14^a is cut away, as at 14^d, at that end 45 of the closure carrying depressed portion 14^f, the decreasing width of flange 14^a preferably extending throughout the curved portion of such end. The particular configuration of portion 14^f is such as to permit it to 50 function as a spoon in removing contents from the container, as indicated in Fig. 2. While the edge at the return bend is sufficiently blunt to prevent cutting action, if the spoon be used for carrying contents to the 55 mouth, it will permit entrance within the container contents especially in view of the decrease in width of flange 14^a at this point.

However, the general arrangement of parts 14^e and 14^f with the cut away end 14^d 60 will aid in manipulating the closure to place it in its seated position. For instance, instead of attempting to seat the closure by a careful manipulation, as is required in connection with circular containers, the closure 65 can be positioned in the following manner.

By bringing one curved end of the open top of the body into contact with that end of the closure in which flange 14^a is of full width, a position in which the closure is slightly canted, the side portions of the closure extending over the sides of the body, and then placing the ball of the thumb into the "spoon" 14^f, or moving the thumb over portion 14^e toward and into the spoon, the closure can be moved to produce a tight fit 70 at the initially-presented end, thus enabling the opposite end to be readily placed in position, the narrowed portion of wall 14^a enabling the flange to readily pass over the body end without damaging the body wall, 75 the walls of the spoon permitting application of pressure without liability of the thumb passing out of proper position to apply the pressure, the thumb pressing the closure to properly seat the open end of the 80 body in its depression.

If desired, that portion of the body open end which extends within the closure may be depressed to an extent which will permit flange 14^a to lie flush with the surface of the 90 body to present a flat label-receiving surface; the bottom may be similarly arranged. Such depressed effect may be provided by cutting away or omitting body material or the body may be manipulated to provide 95 such depressed relation as for instance, is disclosed in Patents Nos. 1,211,873 and 1,212,147.

As hereinbefore pointed out, it is preferred to form the body portion of the container of paper-board or its equivalent. This not only provides for lower cost of manufacture, but in addition, permits of a more efficient sealing effect with the metallic closure and also enables the closure to be 105 manufactured in a simpler and less expensive manner, due to the fact that wall thickness of the body may be increased without producing an excessive weight of material. This enables the endless depression 14^c of 110 the closure to be more readily produced, especially since there is no requirement that walls 14^a and 14^b be in exact parallelism.

While containers having portions of circular form and formed of paper-board have 115 been heretofore employed for the purpose, these structures generally have a length and diameter such as would prevent being carried in the vest pocket. On the contrary the container of the present invention is not 120 only shaped so as to provide a ready positioning in the vest pocket and protection against distortion, but the structure may have such length as to provide maximum capacity, the only limitation being to not 125 exceed the length of the pocket which is to receive the container.

While the flat-sided arrangement of the body of the present invention offers less resistance to side wall collapsing than that 130

of the body of the circular container, no disadvantage results because of the ability to prevent such collapsing effect through the form of the closure. In addition, the 5 particular configuration enables the formation of a closure which is capable of being readily shaped to increase the stability thereof by the use of strengthening ribs or structures serving the function of such rib, 10 as for instance, the rib which connects portion 14^e with wall 14^b, together with the wall which joins portions 14^e with wall 14^b, together with the wall which joins portions 14^e and 14^f. Obviously, the shape is such as 15 to be readily formed by dies.

These advantages, together with those resulting from the ability to apply the closure without requiring careful manipulation, the 20 ability to use the closure as a commodity-moving implement, and the ability to produce the structure at a materially decreased cost of manufacture, render the structure one especially adapted for use in meeting the 25 onerous conditions which are present in uses of this kind, and more particularly where the cost of manufacture is limited by the selling price of the filled container.

While I have shown a preferred way of carrying the present invention into effect,

it will be understood that changes and modifications therein may be required or desired to meet the exigencies of use, and I desire to be understood as reserving the right to make any and all such changes as may be found desirable or necessary in so far as the 30 same may fall within the spirit and scope of the invention as expressed in the appended claim.

What I claim is:

As a new article of manufacture, a 40 closure for commodity-containers of the elongated mouth type, said closure having opposed rising and descending walls adapted to form a depression to receive the walls of the open top of the container, said rising 45 wall corresponding in contour with and adapted to closely fit the exterior of the container open top, said closure having a raised portion leading from a portion of said descending wall to produce an intermediate structure located on different planes, said raised portion acting to support the descending wall against distortion at the sides, the remaining portion of such structure being adapted to act as a commodity- 50 receiving depression.

In testimony whereof I affix my signature.
JONATHAN PETERSON.
